DESIGN FOR A CORK PULLER

James E. Peterson, Los Angeles, Calif.

Application February 12, 1946, Serial No. 126,509

Term of patent 3½ years

(Cl. D44—29)

To all whom it may concern:

Be it known that I, James E. Peterson, a citizen of the United States and a resident of Los Angeles, California, have invented a new, original, and ornamental Design for a Cork Puller, of which the following is a specification, reference being had to the accompanying drawing, forming part thereof.

Referring to the drawing:

Figure 1 is an elevational view of one side of a cork puller showing my new design, with the handle in locked position;

Figure 2 is an elevation as viewed from the opposite side of the device of Figure 1; and

Figure 3 is a top plan view of the device.

I claim:

The ornamental design for a cork puller, as shown.

JAMES E. PETERSON.
